US00D639002S

(12) **United States Design Patent**
Dunn et al.(10) **Patent No.:** **US D639,002 S**
(45) **Date of Patent:** **** May 31, 2011**(54) **DIAPER PAIL BAG**(75) Inventors: **Steven B. Dunn**, Beverly Hills, CA (US); **Mark A. Hatherill**, Beverly Hills, CA (US); **Kevin D. Johnson**, Tarzana, CA (US)(73) Assignee: **Munchkin, Inc.**, North Hills, CA (US)(**) Term: **14 Years**(21) Appl. No.: **29/346,334**(22) Filed: **Oct. 30, 2009**(51) LOC (9) Cl. **07-07**(52) U.S. Cl. **D32/37**(58) Field of Classification Search **D3/303, D3/304, 201, 287; D9/702-706, 720, 724, D9/734, 414, 424, 430-432, 907; D32/37; 150/107; 222/478; 4/484; 383/34, 35, 906**

See application file for complete search history.

(57) **CLAIM**

The ornamental design for a diaper pail bag, as shown and described.

DESCRIPTION

FIG. 1 is a perspective view showing our new design;

FIG. 2 is a bottom plan view;

FIG. 3 is a top plan view;

FIG. 4 is a first side elevational view;

FIG. 5 is a second side elevational view;

FIG. 6 is a front elevational view; and,

FIG. 7 is a rear elevational view.

The broken line showing on the drawing disclosure is for illustrative purposes only and forms no part of the claimed design.
